DRUM FOR BURNING AND AGGLOMERATING.

1,394,293.

Specification of Letters Patent.

Patented Oct. 18, 1921.

Application filed June 10, 1919. Serial No. 303,116.

To all whom it may concern:

Be it known that I, JOHAN SIGISMUND FASTING, a subject of the King of Denmark, residing in 9 Monrads Allé, Valby, near Copenhagen, Denmark, have invented certain new and useful Improvements in Drums for Burning and Agglomerating, of which the following is a specification, reference being had to the accompanying drawings, forming a part hereof.

This invention relates to rotary drums for burning and agglomerating, and it has for its general purpose to increase the capacity of output and the working economy of such apparatus.

In rotary cement kilns for burning slurry an increased direct transmission of heat from the products of combustion to the cement slurry under treatment has been the principal concern of the art on the theory that the efficiency would be substantially proportional to such direct transmission. Accordingly, improvements in structures in the interior of the kiln drum have been of such character as might increase the surface of the slurry rather than the superficial area of the inner wall of the kiln. It has now been found, however, that the capacity and working economy of kilns are primarily dependent upon the amount of heat transmitted to the material from the inner wall or lining of the kiln. Another factor, however, is the uniform conveying of the material through the kiln in such manner as to maintain the material in what may be termed a collective mass and without dispersion of the charge with undue agitation and whirling of the finer particles thereof. But while this uniform and steady conveying of the bulk of the material through the mill must be maintained and while the greatest possible quantity of material must be constantly maintained in engagement with some portion of the inner wall or lining of the kiln, the desirability of exposing the greatest possible amount of material to the products of combustion cannot be ignored. Accordingly, the present invention has for its object to construct an improved kiln which shall include means effective to insure the heating of the material, primarily by absorption of the heat from the inner wall of the kiln and, secondarily by direct contact

with the products of combustion, and which shall, at the same time, bring about the steady and uniform conveying of the material through the kiln without permitting the undesirable dispersion or whirling of the finer particles thereof. In constructing a kiln with means to accomplish the stated results many variable factors must be taken into consideration. In the first place, a kiln varies in temperature at different points throughout its length to very wide degrees. Accordingly where the inner wall or lining might have its superficial area increased at one point by structures of certain material, this material could not be used at other points because of the different thermo conditions. Again, the material of the structures employed for increasing the superficial area of the inner wall or lining must be of such specific heat and yet of suitable conductivity in view of the character of the material, its speed of travel and the temperature of the gases that it will store heat and yet give it up to the material being burned. Another variable factor which affects the construction of a kiln adapted to effect the stated objects is the character of the material to be treated. For instance, in a kiln for treating slurry the material is much wetter at one end than at the other. At the section where the material is wet the contour of the inner wall of the mill must be such as to prevent undue clogging and yet at the section where the material is drier, the contour of the lining can be much more irregular since the material will not adhere so readily to such irregular surfacing. Another requirement to be considered in realizing the most efficient action is that for uniform and steady conveying of the material in a collective mass through the drum. This conveying is brought about most advantageously by constructing the inner wall of the kiln of such form as constantly to elevate the material and keep it in motion.

In carrying out the objects stated the improved kiln is provided in its lining or on its interior wall with rings, segmental ribs or grooves which are of such material, form and relation to insure an increased output of the kiln and greater economy in its operation. Reference is now to be had to the accompanying drawing for a somewhat con-

ventional illustration of different types of wall construction in kilns embodying the improvements. In the drawing—

The figure is a longitudinal view in vertical section through a kiln of improved construction.

In the drawing the feed end of a drum is indicated at *a*, the sintering zone at *b*, and the discharge end for the burnt material at *c*. In such a drum, as is well known, the hottest sections are nearest to the sintering zone. Further, the material is the wettest at the section more remote from the sintering zone. In realizing the hereinbefore stated objects of the invention the drum is provided on its inner wall or in its lining with grooves or rings which will increase the superficial area of the inner surface of the drum so as to increase the transmission 10 of heat therefrom to the material, which will still expose the greatest amount of material to the products of combustion and which will cause a constant and uniform conveying of the material in a collective 15 mass through the drum and keep down the dispersion thereof and the whirling of the finer particles. It has been found in practice that cast iron rings, such as are indicated at *e*, can be employed to advantage in 20 the section of the drum more remote from the sintering zone *b*, these rings being capable of storing heat and yet transmit it to the material to be treated. These rings when placed in a drum receiving wet slurry will 25 be spaced sufficiently to afford some lateral support for the material between them so as to carry the slurry well up the wall of the drum during rotation of the latter, and yet prevent the wet material from collecting 30 between the rings. In the hotter sections of the drum, nearer to the sintering zone *b*, the cast iron rings *e* will not stand the heat, so the inner lining of the drum is formed with ribs *d* of any suitable material, 35 such as ordinarily employed in kiln linings. These ribs *d* serve all of the purposes point-

ed out with respect to the ribs *e* and, according to the degree of dryness of the material in their sections, can be spaced closer together than the rings *e* since the material 50 will have less tendency to clog. The ribs *d* give some lateral support to the material, serving to convey it constantly and uniformly through the drum and yet maintain it in a collective mass and minimize the dispersion or whirling of the finer particles. The material passing through the drum is heated largely from its contact with the surface of the inner wall of the kiln, the superficial area of this surface being greatly increased by the ribs *d* and *e*. 55

I claim as my invention:

1. In a rotary kiln, heat storing and heat transmitting devices possessing different heat storing and heat transmitting properties carried with the inner wall of the drum and extending generally at right angles to the direction of travel of the material to be treated and to the products of combustion and spaced with relation to each other and affording some lateral support to said material. 65

2. In a drum for burning, and agglomerating, having a feed end and a discharge end with a sintering zone therebetween, rings 70 of metal capable of storing and transmitting heat supported on the lining adjacent to the feed end and remote from the sintering zone and extending generally at right angles to the direction of travel of the material and spaced to afford some lateral support for the material while transmitting heat thereto, and additional ribs of heat 75 resistant material adjacent to the sintering zone and spaced to afford lateral support for the material while transmitting heat thereto. 80

This specification signed and witnessed this seventh day of April A. D. 1919.
